MAILBOX AND PROTECTIVE PARTITION
THEREFOR

Sam Barlick, New York, N. Y.

Application October 29, 1949, Serial No. 124,377

1 Claim. (Cl. 232—25)

1

This invention relates to a tamper-proof mail box.

It is an object of the present invention to provide a mail box wherein the lock will be amply protected with heavy metal and will be encased by portions of the box to prevent access to the lock from any of a plurality of directions from within or without the box, and wherein the lock element is heavily encased upon the cover.

Other objects of the present invention are to provide a tamper-proof mail box for preventing access to the lock which is of simple construction, inexpensive to manufacture, compact, convenient to use, and efficient in operation.

For other objects and for a better understanding of the invention, reference may be had to the following detailed description, taken in connection with the accompanying drawing, in which

Fig. 1 is a perspective view of the armor immediately surrounding the lock.

Fig. 2 is a vertical sectional view of the mail box taken generally on line 2—2 of Fig. 1.

Fig. 3 is a transverse sectional view of a part of the mail box taken on line 3—3 of Fig. 2.

Fig. 4 is a vertical sectional view of the mail box taken generally on line 4—4 of Fig. 2.

Figs. 5 and 6 are respectively vertical sectional views of modified forms of the mail box.

Referring now to the figures, 10 represents a wall having a recess into which is fitted mail box 11 embodying the features of the present invention. This mail box will lie in the recess and its front face will be flush with the front face of the wall. The mail box is made of heavy stock and has a rear wall portion 12, a bottom portion 13, a top portion 14 and side portions 16 and 17. The bottom portion 13 has a depending flange 18 which is fixed in the wall face. The box can be secured within the wall in any safe and secure manner.

Within the box are a plurality of bottom compartments 19 having partitions 21. Extending across the front of the box is a hinge 22 to which doors 23 leading to the respective compartments 19 are connected in order that access can be had to the different compartments by the individuals using the letter box. Above the hinge 22 is a top cover 24 which is opened by the mailman to supply the different compartments 19 of the box with the mail.

Upon the rear face of the cover 24 is a heavy socket 25 in which is fixed a lock 26. This socket has laterally extending top flanges 27 to which a clamping plate 28 is connected by screws 29.

5 to fix the lock 26 in place within the socket 25. The lock has a latch member 31 which can be projected upwardly into a recess provided on the top portion by a depending part 33 of the top portion and a depending member 34. In the cover 24 is an opening 35 through which a key can be extended for entry into the lock 26.

On the opposite side of the lock is another key opening 36. The socket 25 is made of heavy stock material or plate and has further flanges 37 and 38 and 39 which have respectively openings 41, 43 and 44 therein for receiving screws or other attaching members for fixing the socket 25 to the inner face of the cover 24.

10 In order that no one can gain access to the lock 26 from any of the compartments 19 when their doors are open, there is provided within the mail box, as shown in Figs. 1, 4 and 6 a thick double partition comprising walls 47 and 20 48 lying respectively at the opposite sides of the socket 25 and of the lock 26. These partition walls 47 extend the full extent or height of the box and upwardly from the bottom portion 13 thereof. These walls thus enclose the lock 26 and prevent access thereto from the inner compartments. The cover 24 has inwardly extending partitions 49 thereon which come into place when the cover is raised.

15 Referring now to Fig. 5, the enclosure for the lock comprises two spaced walls 51 and 52 which are connected together at 53 adjacent the hinge 22. These walls 51 and 52 do not extend to the full bottom of the box. This provides for greater space in the bottom of the box.

25 In Fig. 6, a different construction is provided wherein a connecting wall is disposed between the partitions 47 and 48. This wall is indicated at 54. It will be apparent that these walls in the various forms of this invention cannot be easily penetrated to gain access to the lock 26 from any one of the compartments 19. Full heavy and armored walls will thereby prevent the tampering with the lock. Furthermore, the lock itself is contained and supported upon a heavy armored socket bracket 25. The lock is protected from the top by the top portion 14 of the box and by the cement wall structure.

30 It will be apparent that the individual users of the mail box in opening their individual compartments 19 will be deprived of access to the lock 26.

35 While various changes may be made in the detail construction, it shall be understood that such changes shall be within the spirit and

scope of the present invention as defined by the appended claim.

Having thus set forth and disclosed the nature of my invention, what is claimed is:

A tamper-proof mail box comprising rear, top, bottom and end walls adapted to fit within a recess within a wall structure, a hinge pin extending across the front of the box between the end portions, the said box being adapted to provide compartments for the individual users of the mail box, individual doors pivoted upon the hinge pin and operable to close the several compartments in the bottom of the box, a main cover hinged upon the hinge pin and extending upwardly therefrom to close the top of the box, 15 a lock fixed to the main cover and engageable with the top portion of the box to secure the cover in an elevated position, lock protective partition walls disposed respectively on the opposite sides of the lock to prevent access to the lock from any one of the compartments, a socket bracket of heavy material having laterally extending upper flanges and adapted to receive the lock, said socket having other flanges for securing the socket to the inner face of the main cover, and a clamping plate adapted to extend over the lock and secured to flanges of the socket bracket for fixing the lock in place against

upward displacement, said socket bracket being of heavy armored material to prevent access to the lock and breakage of the same.

SAM BARLICK.
